STOCKING INSPECTING DEVICE

Filed March 19, 1929

UNITED STATES PATENT OFFICE

AUGUST C. SCHOEN, OF LANSDALE, PENNSYLVANIA

STOCKING-INSPECTING DEVICE

Application filed March 19, 1929. Serial No. 348,223.

My invention relates to a new and useful stocking inspecting device particularly adapted for supporting and expanding or distending ladies' hosiery before the same is dyed for the purpose of disclosing any imperfections in the knitting thereof.

My invention further relates to a novel device of this character which in addition to enabling the operator to determine the condition of the stocking will also facilitate the automatic turning inside out of a stocking during its withdrawal from said device, thus reducing by one the operations or steps preceding the dyeing of such stockings.

15 It is necessary in the manufacture of stockings first to ascertain before such stockings are dyed that the same are free from knitting imperfections and to mend such imperfections if any before said stockings are dyed.

20 It is further necessary to turn the stockings inside out before they are subjected to the dyeing operation.

To accomplish these results it has heretofore been the general practice to spread or 25 stretch the stocking on a support of a slightly larger size so that the stitches of the stocking are distended to facilitate close and accurate observation. In this practice it was necessary to have supports of various sizes 30 corresponding to the various sizes of stockings. In order to guard against excessive or improper stretching or possibly the tearing of the stockings it is always necessary to employ a relatively smaller support, that 35 is, one which does not expand the stocking to the maximum limit possible thereby sacrificing from the utility of such support in as far as it serves to disclose the knitting imperfections of the stocking.

40 After the stocking has been inspected, and if necessary mended, it is necessary for the operator manually to turn the stocking inside out before the dyeing process can be attempted. A further disadvantage of the 45 practice heretofore prevailing, resided in the fact that no efficient, adequate means were provided for the proper expansion of the heel and instep portions of the stockings.

It is the object of my invention to remedy 50 the defects hereinabove outlined and to pro-

vide an expansible support which may be used for the inspection of stockings of various sizes, which properly expands and spreads or distends the heel and instep as well as the body or leg portions of the stocking, and 55 which will so support and engage the stocking that after the latter has been inspected, and if necessary mended, it will be automatically turned inside out by the mere withdrawal of said stocking from said support.

To the above ends, my invention consists of an inner, inexpensive, upwardly movable frame; an outer, laterally expansible, stationary frame; means carried by the upper 65 end of said inner frame for expanding the toe, heel, and instep portions of a stocking; and means for actuating said inner and outer expansible frame for spreading or distending the entire area of a stocking mounted on said outer frame.

70 My invention further consists of means for limiting the expansion of said outer expansible frame to guard against an excessive or improper expansion of the stocking, thereby eliminating all danger of tearing or ripping the same.

75 My invention further consists of means carried by said frames for engaging the foot portion of the stocking while the latter is being withdrawn from said expansible frame or support, thus effecting an automatic turning inside out of said stocking, during its withdrawal from my novel device.

80 For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

85 In the accompanying drawings:

Fig. 1, represents a side elevation of a stocking inspecting device embodying my invention.

tion with a stocking shown in dotted lines mounted thereon.

Fig. 2, represents, on an enlarged scale, an end elevation of the upper portion of Fig. 1.

Fig. 3, represents, on an enlarged scale, a fragmentary vertical sectional view of the bottom portion of Fig. 1, certain parts being shown in elevation.

Fig. 4, represents a view partly in section and partly in plan showing details of construction.

Fig. 5, represents a fragmentary end view of Fig. 4 showing details of construction.

Referring to the drawings, in which similar numerals of reference indicate corresponding parts, 1 designates a stocking inspecting device embodying my invention, comprising the inner, rigid, triangular frame 2 composed of the bottom cross member 3 and the upright converging members 4 the upper ends of which merge into or are suitably secured to the upright standard 5. The upright converging members 4 are inter-connected by transverse cross bars 6, to the lowermost one 7 of which is connected the upper end of the plunger 8, which also passes through or is integral with the bottom cross member 3 of the frame 2, as will be understood from Fig. 1. The plunger 8 is guided in the tubular bearing or sleeve 9 and carries at its lower end the sleeve or collar 10 adjustably secured thereto by the set screw 11. 12 designates a foot pedal fulcrumed to the support 13 at 14 and pivoted to the lower end of the plunger 8 at 15 so that a downward pressure on the outer end of said foot pedal will result in an upward movement or elevation of the plunger 8, thus raising the inner rigid frame 2 carried by the upper end of said plunger. At about the ends of the cross bars 6 and 7 interconnecting the converging uprights 4 are pivoted the inner ends of the links 18, the outer ends of which are pivoted to the lugs 20 on the inner surfaces of the outer converging uprights 21 of the outer expandible frame 22 so that the raising of the inner frame 2 by the action of the pedal 12 results in expanding or distending the outer expandible frame 22 in the direction of the arrows. The lower ends of the outer converging uprights 21 are notched as at 24 and are guided in the slots 25 at either end of the bottom guide plate 26, as will be understood from Figs. 1, 3, 4, and 5. 27 designates a collar engaging the upper end of the tubular bearing 9, and carrying the set screw 28, which serves to prevent the upward movement of the bottom guide plate 26, it being understood that the bearing 9 is provided with the hub 29, the annular flange 30 of which is secured to the table or other support 31 by the bolts or other fastening devices 32. To the upper end of the upright standard 5 is secured the cross bar 34, which forms a rest for the upper converging ends

of the outer uprights 21. The upright 5 also carries the arched support 35, hereinafter further referred to. 36 designates a rounded knob suitably secured to the standard 5 and provided with the upper and lower inclined plates 37 whose function will be hereinafter fully set forth. The uprights 21 are bulged as at 50 for a purpose hereinafter set forth. The operation is as follows:

The stocking 39 to be inspected, shown in dotted lines in Figs. 1 and 2, is drawn downwardly over the outer converging uprights 21 of the expandible frame 22 until the toe portion 40 of the stocking rests upon the arched support 35 carried by the upright standard 5 and the heel portion 41 of the stocking is engaged by the knob 36 while the portions of the foot of the stocking intermediate the heel and the toe and the heel and the ankle are distended over the upper and lower inclined plates 37. The foot pedal 12 is then depressed to raise the inner rigid frame 2 carried by the plunger 8. This expands the outer converging uprights 21 in the direction of the arrows seen in Fig. 1, thus spreading or stretching the stocking 39 to make the stitches of the stocking more clearly visible and thus enable the operator to ascertain any defects or imperfections in the knitting thereof. The inner frame 2, the outer converging expandible frame 22, and the bottom guide plate 26 are rotatably mounted on the plunger 8 so that the entire construction may be revolved to permit the inspection of the entire surface of the stocking 39. To prevent excessive raising of the plunger 8 and consequent excessive expansion of the outer frame 22 which might result in damage to the stocking 39, I have provided the collar 44 which is secured to the plunger 8 by the set screw 45 so that when said collar comes in contact with the lower end 46 of the tubular bearing 9 it acts as a stop to limit the upward travel or movement of the plunger 8, thereby limiting the expansion of the outer expandible frame 22. It will be understood that the collar 44 is adjustably secured to the plunger 8 and that the position of said collar on said plunger is determined by the size of the stocking 39 being inspected, thus rendering my entire novel device adjustable for the inspection of stockings of various sizes.

After the stocking has been inspected, and if necessary mended, it is turned inside out preparatory to being put through the dyeing process. In order to turn the stocking inside out by means of my novel device, it is merely necessary to grasp the top 47 of the stocking and to pull the same upwardly. Due to the fact that the body of the stocking is more or less frictionally engaged by the outer surface of the converging upright 21, and due to the fact that the heel portion of said stocking is engaged by the knob 36, it will be evi-

dent that by merely pulling upwardly on the top of the stocking in the manner stated, the stocking will be automatically turned inside out as the stocking is being withdrawn from the inspecting device. In order to insure the turning inside out of the toe portion 40 of the stocking I have provided the bottom free ends 48 of the arched toe support 35 which, as will be seen from Fig. 1, tend to engage the foot portion of the stocking at a point in proximity to the toe portion thereof so that the toe portion of the stocking is turned inside out completely, by the mere withdrawal of said stocking from said inspecting device in the manner set forth. When the pressure on the lever 12 is relieved, the expandable frame 22 drops into the collapsed position shown in Fig. 1.

It will thus be seen that I have devised a novel inspecting device which is adapted for the inspection of stockings of various sizes, and that my novel device further serves to enable the stocking to be automatically turned inside out by the mere withdrawal of the stocking from said device, without requiring any further attention on the part of the operator or attendant.

The bulge 50 formed in the uprights 21 serves to stretch the stocking at or about the narrowed portion intermediate the ankle and calf portion thereof to open such blind stitches (if any) as may be found in the narrowing of said stocking.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new and desire to secure by Letters Patent, is:

1. In a device of the character stated, an inner rigid frame, an upper arched support carried by the upper end thereof, an outer expandable frame of substantially the same contour, links pivotally connected to said frames, a plunger connected to the bottom of said inner rigid frame, means engaging and guiding the lower ends of said outer frame, and means for raising said plunger and inner frame to expand said outer frame.

2. In a device of the character stated, an inner substantially triangular rigid frame, an upper arched support carried by the upper end thereof, a horizontally projecting support carried by the upper portion of said frame in proximity to and below said arched support, an outer expandable frame of substantially triangular contour, pivotal connections intermediate said inner and outer

frames, and means for raising said inner frame to expand said outer frame.

3. In a device of the character stated, an inner rigid frame, a plunger connected to the bottom end thereof, a stocking toe support carried by the upper end of said frame, a stocking heel support carried by said inner frame in proximity to and below said toe support, an outer expandable frame, pivotal connections intermediate said frames, a guide for the lower ends of said outer frame, and means for raising said inner frame within said outer frame to expand the latter.

4. In a device of the character stated, a rigid vertically movable inner frame, an expandable, vertically immovable, revolvably mounted outer frame adapted to receive and support a stocking, pivotal connections common to said frames, means for raising said inner frame to expand said outer frame and distend said stocking, and means carried by the upper portion of said inner frame for engaging the heel and toe portions of said stocking to effect a turning inside out of said stocking while the latter is being withdrawn from said outer frame.

5. In a device of the character stated, a rigid, vertically movable inner frame, a stocking toe supporting and engaging means carried by the upper end of said frame, a stocking heel supporting and engaging means carried by the upper end of said frame in proximity to and below said toe supporting means, an expandable, vertically immovable outer frame, pivotal connections common to said frames, said outer frame being adapted to serve as a support for the body of a stocking, and means for raising said inner frame to expand said outer frame to stretch a stocking carried thereby, said toe and heel engaging means being adapted to engage said parts while the stocking is being withdrawn from said outer frame to effect a turning inside out of said stocking.

6. In a device of the character stated, a plunger, means for raising and lowering said plunger, an inner rigid frame carried by the upper end of said plunger, an outer laterally expandable frame pivotally connected to said inner frame and having its lower ends guided in and engaged by a stationary rotary support, an upper arched support carried by the upper end of said inner rigid frame, and a horizontally disposed upwardly and downwardly extending stocking heel support carried by the upper portion of said inner rigid frame in proximity to and below said upper arched support.

7. In a device of the character stated, a stationary horizontal support, a tubular bearing therein, a plunger extending through said bearing, means for actuating said plunger upwardly, means for limiting its upward movement, an inner rigid triangular frame carried by said plunger, an arched

support carried by the upper end of said inner frame, a horizontally projecting substantially triangular stocking heel support carried by the upper portion of said inner frame, below and in proximity to said arched support, a lower longitudinal guide plate revolvably carried by said plunger intermediate said stationary horizontal support and the bottom end of said inner frame, said 10 guide plate being incapable of vertical displacement, a pair of outer, oppositely disposed, upwardly converging uprights having their lower ends engaged in and guided by slots in the opposite terminals of said guide 15 plate, and connecting links having their inner ends pivoted to the outer surfaces of said inner frame and their outer ends pivoted to the inner surfaces of said outer converging uprights, whereby the latter are actuated 20 laterally in opposite directions by the upward movement of said inner frame due to the upward movement of said plunger.

8. In a device of the character stated, an inner rigid frame, an outer expansible frame 25 of substantially the same contour adapted to carry a stocking, links pivotally connected to said frames, a plunger connected to the bottom of said inner frame and means for raising said plunger and said frame to expand 30 said outer frame, the latter being outwardly bulged at that portion thereof which corresponds to the narrowed portion in the body of said stocking.
